LOCOMOTIVE BODY

Edward Gray, Detroit, Mich., assignor of one-half to Gar Wood, Detroit, Mich.

Application May 15, 1933, Serial No. 671,177

7 Claims. (Cl. 105—172)

The present invention relates to railway rolling stock, and more particularly to a novel locomotive body construction.

The primary object of the present invention is to provide a locomotive body, formed of sheet metal, with the parts thereof arranged to provide a box construction and integrally united, as by welding, to provide for strength and durability. More particularly, the body is provided with spaced apart horizontal walls which are maintained spaced apart and reinforced by transverse walls whereby they provide a floor construction embodying a plurality of tanks. The boiler which forms a necessary part of the locomotive power plant, is integrally united with side walls and with internal bracing walls which extend vertically from the floor to the boiler, the vertical walls being integrally united, as by welding, with the floor, the side walls and with the boiler. To provide for greater strength and rigidity the vertical reinforcing walls are themselves reinforced by transverse or horizontal reinforcing walls and these horizontal reinforcing walls provide a support for cylinders of a Diesel engine, thus adapting the present locomotive body for the reception of a combined steam and Diesel engine power plant. In order to cool the cylinder walls of the Diesel engine the horizontal reinforcing walls are formed of box construction providing water channels through which water may be circulated to the cylinder walls.

With the above and other objects in view the invention consists in matters more particularly pointed out hereinafter with reference to the accompanying drawings, in which

Fig. 1 is a fragmental vertical section;

Fig. 2 is a fragmental vertical section which is a continuation of Fig. 1;

Fig. 3 is a horizontal section taken on the line 3—3 of Fig. 1;

Fig. 4 is a horizontal section which is a continuation of Fig. 3;

Fig. 5 is a vertical section taken on the line 5—5 of Fig. 1;

Figs. 6 and 7 are vertical sections taken on lines 6—6 and 7—7 of Fig. 2, respectively;

Fig. 8 is a fragmental transverse section illustrating the power plant assembly in the body, and

Fig. 9 is a longitudinal vertical section corresponding with Fig. 8.

Like characters of reference are employed throughout to designate corresponding parts.

The body of the present locomotive is constructed with a cab 1 at the extreme rear end thereof, and extending in a forward direction

from the cab is a housing that is divided into two compartments 2 and 3, the compartment 2 being located directly in front of the cab 1 and the compartment 3 being at the extreme forward end of the locomotive body. The floor of the cab 1 comprises two, vertically spaced, horizontal plates 4 and 5, the lower plate 5 being provided with a bearing 6 adapted for the reception of a king pin on a wheeled truck. The cab construction is more clearly shown in Figs. 1 and 5 wherein it is readily apparent that the two floor plates 4 and 5 are integrally united with the vertical side walls 7, which are also integrally united with the roof 8. The two floor plates 4 and 3 are spaced rigidly apart by transverse reinforcing walls 9 which divide the space therebetween into tanks. The rear end of the cab 1 is closed by a rear wall 10, integrally united with the other walls and plates of the cab, and at its forward end by a bulkhead 11 which divides the cab from the compartment 2, the bulkhead 11 being integrally united with the side walls and floor plates of the cab.

As may be seen upon reference to Figs. 3 and 4, the side walls of the cab 1 are continuously extended forwardly to the front end of the locomotive body, the portions of the side walls which relate to the cab being designated 7, the portions relating to the compartment 2 being designated 7a and the portions which relate to the forward compartment 3 being designated 7b. The two side wall portions 7a, in front of the cab 1, are formed with substantially horizontal portions extending inwardly with respect to the compartment 2, each horizontal portion being disposed at the top of its respective wall 7a. The inwardly extending portions are designated 12 and may be seen more clearly in Fig. 6. The walls 12 are welded to a boiler 14 as designated at 13 and thus become an integral part of the boiler. The side walls 7a and the horizontal walls 12 are reinforced by transverse walls or webs 15, the walls or webs 15 being located on opposite sides of the compartment 2 in pairs. Transverse reinforcements 16 extend across the top of the compartment 2. The portions or members 16 which unite the walls or webs 15 are integrally united, by welding, to a wall 17 of the boiler 14.

The transverse webs 15 are formed at 18 for the reception of bearings for supporting a crank-shaft of a Diesel engine, the bearings being shown at 19 in Fig. 8 as supporting the crank-shaft 20 of a Diesel engine.

The floor of the compartment 2 is formed of two vertically spaced horizontal plates 21 and 22.

closed at the sides of the compartment by vertical walls 23. The floor plates 21 and 22 are supported from the side walls 1a by extensions 24 on the transverse walls or webs 15, likewise the 5 vertical walls 23, the side walls 1a being welded to the web extensions 15 and the plates 21 and 22, and the vertical walls 23 being welded to the web extensions 24. As may be seen in Figs. 2 and 10 6, the extensions 24 on the walls or webs 15 divide the space between the floor plates 21 and 22 into a plurality of tanks.

In order to enclose the bearings 19 and the crankshaft 20, and yet to permit access thereto when such is desired, removable cover plates 25 15 are provided. For the purpose of supporting the plates 25 the side walls 1a are provided with flanges 26 and the vertical walls 23 with flanges 27. No securing means has been illustrated as holding the plates 25 in place but it will be understood that any suitable type of fastening elements may be employed.

Spaced in a vertical plane above the floor plate 21 are horizontal walls 28 of box construction, the walls 28 being disposed between pairs of webs 25 15 and welded thereto for the purpose of rigidifying the same. As may be seen in Fig. 8, the horizontal walls 28 constitute shelves for the support of cylinder walls 29 of a Diesel engine and, being hollow, provide means for conveying cooling 30 liquid to the cylinder walls.

The compartment 3 is provided with a floor formed of vertically spaced plates 30 and 31, supporting a bearing 32 for the reception of a king pin on a wheeled truck, the plates 30 and 31 being 35 transversely reinforced by walls forming water tanks 35a. Welded to the upper plate 5, are vertical walls 33 that are joined to the side walls 7b by horizontally extending portions 34 to provide water tanks 35 which communicate 40 through openings 38 with the water tanks 35a. A continuous channel 36 extends from the tanks formed between the floor plates 4 and 5 of the cab 1 and the water tanks 35a thus provided between the floor plates 30 and 31 of the compartment 45 3, the channel 36 being separated from the tanks 37 formed between the floor plates 21 and 22 of the compartment 2. The tanks 37 are provided for the reception of fuel oil.

The locomotive body thus formed is of comparatively light weight, inasmuch as it avoids the use of heavy castings and forgings, and the manner in which the body is fabricated of sheet metal shapes welded together with the various necessary accessories, such as water and fuel oil tanks, 55 built into the body provides for strength and durability and results in a locomotive wherein the power plant may be located between the forward and rear trucks and wherein the entire weight, including the liquid weight, is equally divided between the forward and rear trucks.

Although a specific embodiment of the invention has been illustrated and described it will be understood that various changes may be made within the scope of the appended claims without departing from the spirit of the invention, and such changes are contemplated.

What I claim is:

1. A locomotive body comprising a hollow floor structure, a boiler spaced above said floor structure, body side walls integrally united with said boiler, said side walls having laterally diverging portions and downwardly extending portions spaced laterally from the side edges of said floor structure and terminating in the horizontal plane 75 of said floor structure, webs integrally united

with said floor structure and extending laterally therefrom, said webs having upwardly extending portions integrally united with said side walls and transverse portions integrally united with said boiler, and removable walls secured to bottom edges of said side walls and to adjacent edges of said floor structure.

2. A locomotive body comprising a hollow floor structure, a boiler spaced above said floor structure, body side walls integrally united with said boiler, said side walls having laterally diverging portions and downwardly extending portions spaced laterally from the side edges of said floor structure and terminating in the horizontal plane of said floor structure, webs integrally united with said floor structure and extending laterally therefrom, said webs having upwardly extending portions integrally united with said side walls and transverse portions integrally united with said boiler, and bearings mounted on the laterally extended portions of said webs and adapted to support engine shafts.

3. A locomotive body comprising a hollow floor structure, a boiler spaced above said floor structure, body side walls integrally united with said boiler, said side walls having laterally diverging portions and downwardly extending portions spaced laterally from the side edges of said floor structure and terminating in the horizontal plane of said floor structure, webs integrally united with said floor structure and extending laterally therefrom, said webs having upwardly extending portions integrally united with said side walls and transverse portions integrally united with said boiler, bearings mounted on the laterally extended portions of said webs and adapted to support engine shafts, and removable walls attached to the bottom edges of said side walls and extending therefrom to said floor structure in a plane beneath said bearings.

4. A locomotive body, as defined in claim 1 characterized in that said hollow floor is composed of vertical side and end walls integrally united with horizontal top and bottom walls, and said webs having extended portions integrally united with the side and top and bottom walls of said floor and dividing the space therein into tanks.

5. A locomotive body as defined in claim 1 characterized in that said hollow floor is composed of vertical side and end walls integrally united with horizontal top and bottom walls, said webs having extended portions integrally united with the side and top and bottom walls of said floor, and vertical walls united with said web extensions and top and bottom walls and cooperating therewith in reinforcing said floor and dividing the space therein into tanks.

6. A locomotive body having a hollow floor structure, side walls spaced laterally of the side edges of said floor structure and having their lower edges in substantially the same horizontal plane as said floor structure, a boiler supported at the top of said side walls, transverse walls integrally united with said side walls and having inwardly extended portions bridging the space between the side walls and adjacent edges of said floor structure, said inwardly extended portions being integrally united with said floor structure, means on said inwardly extended portions for supporting power plants, and removable walls secured to bottom edges of said side walls and adjacent edges of said floor structure.

7. A locomotive body having a hollow floor structure, side walls spaced laterally of the side

edges of said floor structure and having their lower edges in substantially the same horizontal plane as said floor structure, a boiler supported at the top of said side walls, transverse walls integrally united with said side walls and having inwardly extended portions bridging the space between the side walls and adjacent edges of said floor structure, said inwardly extended portions

being integrally united with said floor structure, means on said inwardly extended portions for supporting power plants, said means comprising hollow shelves having dividing walls forming fluid conveying channels therein, and removable walls secured to bottom edges of said side walls and adjacent edges of said floor structure. 5

EDWARD GRAY.
